UNITED STATES PATENT OFFICE

1,984,616

TENTER CLIP

John H. Williams, Providence, R. I.

Application January 11, 1933, Serial No. 651,190

2 Claims. (Cl. 26—62)

This invention relates to improvements in tenter machines and is directed more particularly to clips for the chains of tentering machines.

The principal objects of the invention are directed to the provision in a tenter machine of a clip having a novel safety lock as one feature for releasably locking the swinging jaw or gate in an open non-clamping position and means as another feature for releasing the jaw and checking the swinging movement of the jaw towards its operable position when released.

The endless chains of tenter machines are formed from pivoted-together devices called clips, each of which includes a swinging jaw or gate member. The lower sides of the jaw members bear on a web of material such as a fabric to clamp the edge to plates or the like. The clips which are hinged or linked together to form the endless chains are arranged so the adjacent inner runs of the chains carry a web of material forwardly through the machine from one end to the other. As the clips round the sprockets at the entrance end of the machine, the jaws swing into web engaging relation and when the clips reach the discharge end of the machine the clips are opened to release the web.

According to this invention means is provided to releasably hold the jaws of the clips in open position from the discharge end of the machine around to the entrance end, and other means are provided to release the jaws so that they may operate with a clamping action. By holding the jaws out of operative engagement with the co-operating clamping parts of the clips excessive wear of the parts is eliminated. To insure the most efficient operation, according to the invention, when the clips are released for the web engaging action, means is provided to check the swinging movements of the jaw so that its web engaging parts will not meet up with co-operating web engaging parts, thereby obviating injury to these parts.

According to a special feature of the invention, the means for releasably locking the jaw in its open position is concealed or enclosed by the tenter clip proper so that there are no projecting parts which may become caught and, thereby, broken or bent which would interfere with the proper functioning of the clips.

Various other novel features and advantages of the invention will be more fully hereinafter referred to in connection with the accompanying description of the preferred form thereof, reference being had to the accompanying drawing, wherein:

Fig. 1 is a side elevational view of a tenter clip embodying the novel features of the invention.

Fig. 2 is a partial plan view on the line 2—2 of Fig. 1.

Fig. 3 is an elevational sectional view on the line 3—3 of Figure 1.

Fig. 4 is a transverse sectional view of the upper part of the clip shown in Fig. 1 to explain certain features of the invention, and

Fig. 5 is a diagrammatic plan view at small scale to explain the operation of certain features of the invention.

Referring now to the drawing more in detail the invention will be fully described.

In Fig. 1 there is shown a tenter clip C which has a plate 2 for underlying the marginal edge of a web, and a gate or jaw 4. The gate is pivoted at 6 to upwardly and forwardly extending arms 8 which are arranged in a spaced relation with reference to the main body of the clip as shown.

Lugs such as 10 on either side of the clip are arranged to be connected to lugs of adjacent clips by suitable pins so that a plurality of the clips may be joined together to form an endless chain such as has been referred to. In ordinary tenter machine construction the endless chains formed by the clips are driven by sprockets located in either end of the machine so that the inner runs of the chains travel forwardly to move a web of material such as cloth or the like from the entrance to the discharge end of the machine.

In the form of the invention shown, a blade 5 is provided in the gate 4 and is arranged so that its lower end will bear on a web of material above the plate 2 and in this way the web is clamped to the plate. A lever 7 extends upwardly from the gate 4 and it will be readily apparent that, by swinging this lever from the position shown in Fig. 1 to the right, the gate will be swung away from the plate to release a web between the lower end of the gate 4 and plate 2. A control member 12 is pivoted at 14 to ears 16 of the clip C and a fork member 18 extends rearwardly at the lower end of the gate. This may be of usual construction and need not be described herein more in detail.

At the discharge end of the tenter machine there are various means provided for swinging the lever 7 to the right to open the gate and release the web. It is to releasably lock the gate in this open position, while the clip is returning on the outer run back to the entrance end of the machine, that one feature of the invention is directed.

In the form of the invention shown, a cross bar 20 extends between the arms 8 and a lock member 19 has its upper end secured thereto as by some suitable means such as screws 22. A free end 23 of the lock member 19 extends in a more or less curved relation downwardly between the arms and from its attachment to the cross bar 20. The lower extremity of the member 19 is curved as shown in Fig. 1 and a slot 24 as shown in Figs. 2 and 3 is provided to permit the necessary movements of the control member 12. It will be noted that the member 19 is located between the arms so as to be more or less protected and so that it will not become caught or contacted with other parts of the tenter machine.

The lower end of the member 19 is arranged so that, as the lever 7 of the gate 4 is swung to the right, the fork 18 of the gate will pass upwardly beyond and rest on the lower end of the member 19 as shown in Fig. 4. Thus the gate is releasably locked in open position, so that its lower end is held out of contact with the plate 2 during the travel of the clip from the discharge end to the entrance end of the tenter machine. In this way, since the parts are held out of contact, the usual wear between the jaw and plate therebelow is obviated.

As another feature of the invention it is desired to release the gate from the locking means as the clips approach the web engaging position and to check the action of the gate. The releasing is accomplished by the provision of a shoe 30, such as shown in Fig. 5, which may have a cam surface 32. As a clip travels forwardly in the direction of the arrow, as shown, the lever 7 thereof engages with the shoe 30 which acts to swing the lever sufficiently to release the fork 18 from the lock 19. In this way the gate or jaw is free for the web engaging function.

In order however to insure that the web engaging parts of the gate will not strike upon the plate or a web thereon with too much force when released the means referred to is provided to check the movements of the lever 7. This is accomplished by a stop shoe 34, against which the lever 7 strikes when released by the spring member 19. In this way as the gate is released, its lower end is held out of contact with the plate or web thereon. As the clips pass by the plate 34 the marginal edge portion of the web will be between the plate and lower end of the gate and therefore when the lever is released by the member 34 the gate is free to bear on the web for the clamping operation.

It will be readily apparent that the releasable lock is adapted to adequately hold the gate in an open position and that lock is so located as to be enclosed or protected by the arms of the clip. This is so the releasable lock will not become caught on objects past which it travels and thereby it is protected against injury.

It will also be observed that the means for releasing the gate is associated with means to limit or check the swinging movements of the gate after it has been released. In this way, the gate after it is released will not swing so that its lower end strikes the plate or web thereon but is limited in its movement so that, when released by the stop shoe, its lower end will bring up against the web for the clamping action without injury to the parts or web.

Various changes and modifications may be made in the form of the invention without de-

parting from the spirit and scope thereof and therefore what it is desired to claim and secure by Letters Patent of the United States is:

1. A tenter machine comprising in combination, a plurality of tenter clips hinged together forming an endless chain, sprockets therefor, each clip including a body and a substantially horizontally disposed web-engaging plate portion and spaced arms integral with the body so as to be held against movement relative to said plate portion and extending upwardly and forwardly from the rear of said plate, a gate pivoted between said arms at the upper ends thereof for swinging movements relative to said plate and having a lower web-engaging portion and a fork extending rearwardly therefrom over said plate, a bar extending between said arms, a lock of resilient strip material having its upper end portion secured to said bar and a portion curved downwardly therefrom between said arms provided with an end portion in the path of movement of the fork and adapted as the gate is swung rearwardly from a forward web-engaging position to a rearward open position to be engaged and flexed downwardly by the fork so as to yieldingly bear upwardly on said fork and releasably lock the gate in open position, an upwardly extending lever provided on each of said gates, a stationary cam adapted to engage said levers to swing the gates towards an open web-engaging position and release said forks from the locks, and a stationary stop member against which said levers abut when said forks are released whereby the forward swinging movement of said gates is checked, the said cam and stop member being disposed in spaced relation so the levers may pass therebetween.

2. In a tenter machine, a tenter clip of the type adapted to be hinged connected to others to form an endless tenter chain, said clip including a body, a substantially horizontally-disposed web-engaging plate portion rigidly associated with the forward side of said body, spaced arms extending forwardly above said plate portion from adjacent the rear side of the body and being integral with said body so as to be immovable relative to said plate portion, a bar member spaced above said plate portion extending between said spaced arms, a control member pivoted between said spaced arms, a gate pivoted between the forward outer ends of said spaced arms for swinging movements relative to said plate portion and provided with an operating lever member extending upwardly from its upper side and a portion on its lower side for co-operating with said plate portion to engage a web therebetween, a fork extending rearwardly from said gate over said plate for actuating said control member, a lock member of resilient strip material secured at its upper end to said bar curving rearwardly, downwardly and then forwardly between said spaced arms below said bar to provide a compressible free end portion in the path of movement of said fork, said free end portion being provided with a slot therein for receiving said control member and being adapted as the gate is swung rearwardly from a forward web-engaging position to a rearward non-web-engaging position to be engaged and flexed downwardly by said fork so as to yieldingly bear upwardly thereon and releasably lock the gate in said rearward position.

JOHN H. WILLIAMS.
